CLAIM

The ornamental design for a base unit for electric kettle, as shown and described.

DESCRIPTION

FIG. 1 is a front, right side, perspective view of a base unit for electric kettle showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a front, right side perspective view showing the claimed design in an environment of use.

The broken lines in FIG. 7 indicate portions of the article that form no part of the claimed design. The broken lines in FIG. 8 depict environment that forms no part of the claimed design.

1 Claim, 8 Drawing Sheets
